DISPLAY RACK AND REEL

Louis A. Macklanburg, Oklahoma City, Okla.

Application April 16, 1931. Serial No. 530,666

3 Claims. (Cl. 242—55.2)

This invention relates to apparatus for displaying and dispensing elongated material such as weather stripping, metal or felt, which is ordinarily shipped and dispensed in coils.

5 The retailing of such material from coils and particularly of the strip metal weather stripping, is frequently quite inconvenient, as the material when it is uncoiled is difficult to control and there is always a liability of the coil itself springing or disintegrating.

The object of the present invention is to provide improved apparatus of a simplified structure which can be shipped with a coil of the material to be dispensed therefrom, if desired, 15 in a very convenient and compact form, and which permits the convenient display of the material and easy removal of small parts for sale purposes.

A further object is to provide apparatus of 20 the character indicated which will permit the forming of small coils and the ready tying of the same.

A further object of the invention is to provide means for ready measuring the coiled material.

Further objects will more particularly appear in connection with the following detailed description.

The invention consists in the novel construction, arrangement and combinations of parts hereinafter more particularly described and claimed.

Two sheets of drawings accompany this specification as part thereof, in which like reference characters indicate like parts throughout.

Figure 1 is a perspective view of one form of the improved apparatus mounted upon a counter with the coil of material in place.

Figure 2 is a vertical cross section through the reel support, showing the reel in side elevation.

Figure 3 is a transverse vertical cross section through the coil rack with a coil in place.

Figure 4 is a fragmentary longitudinal vertical cross section through the reel rack showing a coil in position.

Figure 5 is a perspective view of a modified form of the apparatus.

Figure 6 is a plan view of the form illustrated in Figure 5.

Figure 7 shows the apparatus illustrated in Figure 5 assembled with a coil of material for transporting purposes.

Figure 8 is a fragmentary side view of Figure 7.

Referring to the drawings, 1 indicates a coil of metal weather stripping; 2 indicates a coil rack which as illustrated is in the form of an open top box of a height substantially half the diameter of the coil which is to be dispensed therefrom. The coil rack 2 is provided with a slot 4 near the bottom of one end through which the free end of the weather strip is threaded.

A winding reel 6 is provided, having spokes 7 and a spindle 8. The periphery of reel 6 is provided with transverse peripheral grooves, notches or inturned loops 9 intermediate the spokes 7, and the spindle 8 is preferably provided with a squared end 15 adapted to receive a handle 16. The loops or notches 9 provide means for passing cords around the coil formed on the reel for tying the same and also facilitates removal of the coil from the reel. A transverse notch 10 is also provided in the periphery of reel 6 for receiving and holding the end 5 of the weather strip.

A reel support of U-shape is provided, having notches 11 in the ends of its legs 12, in which notches spindle 8 of the reel is adapted to seat. The reel support can be secured to a counter by its intermediate part 13 and a screw 14, or it may be bolted to reel rack 2 as through hole 21 above slot 4.

In the modified form illustrated in Figures 5 to 8, the reel rack consists of a loop 18 adapted to embrace the coil 1 diametrically, this loop 18 being supported by vertical standards 17, one on each side, which standards are in turn associated with a base 20. In this form, the U support 12 for the reel can be secured to the coil loop as by bolt or screw 19.

For conveniently dispensing weather strip with the apparatus thus described, it is desirable that the weather strip be provided with indicia spaced apart unit distances, by preference one foot.

In operation the coil rack and reel support will be assembled as illustrated in Figure 1 or Figure 5 and the coil of material to be dispensed will be placed in the coil rack. As small quantities are called for, the end 5 of the strip will be inserted in notch 10 on the reel and the reel wound either by hand or by handle 16, the units indicated by marks 20 being counted until the desired amount is wound upon reel 6. At this point, a pencil or pin 19 can be inserted in one of the loops or notches 9 which will operate to effectively brake reel 6 while the strip is severed. Cords 21 can be passed through loops or notches 9 as illustrated in Figure 7 and tied about the small coil preliminarily to removing the coil from reel 6 which can

be readily done by lifting the reel from the U support 12.

In shipping, it will be apparent that with either type of apparatus, the reel can be shipped inside 5 of a coil of material, the coil placed in the coil rack and the U-shaped reel support nested over the coil so that a coil of material together with the complete vending and display apparatus can be shipped in a parcel only slightly larger than 10 that of a coil alone.

Having thus fully described my invention, I claim:

1. A coil rack adapted to hold and in which a coil of elongated material can rotate, a reel, a 15 reel support adapted to nest over the coil in the coil rack and means for associating the reel support with the coil rack to permit reeling material directly from a coil in the coil rack.

2. A coil rack comprising a loop adapted to 20 encircle a coil on a diameter thereof centrally

positioned supports on each side of the loop and a base secured to said supports, a reel, a reel support adapted to nest over the coil in the coil rack and means for associating the reel support with the coil rack to permit reeling material directly from a coil in the coil rack. 80

3. A coil display and dispensing device comprising a coil rack which includes means for engaging the coil diametrically thereof and supporting means therefor, a reel having a transverse peripheral notch, a transverse peripheral slot and a spindle, a U-shaped reel support adapted to embrace the coil radially, having notches in the ends of its legs to receive the ends of the reel spindle and means for operatively associating the coil rack, reel and reel support whereby the coiled material can be wound from the coil positioned in the coil rack directly to the reel. 85 90
